Robert Pierpont Inventor
By Atty Seymour & Carre

UNITED STATES PATENT OFFICE.

ROBERT PIERPONT, OF NEW HAVEN, CONNECTICUT.

FEEDING MECHANISM FOR SEWING-MACHINES.

SPECIFICATION forming part of Letters Patent No. 668,414, dated February 19, 1901.

Application filed May 22, 1900. Serial No. 17,529. (No model.)

To all whom it may concern:

Be it known that I, ROBERT PIERPONT, of New Haven, in the county of New Haven and State of Connecticut, have invented a new

5 Improvement in Feeding Devices for Sewing-Machines; and I do hereby declare the following, when taken in connection with the accompanying drawings and the letters of reference marked thereon, to be a full, clear, and 10 exact description of the same, and which said drawings constitute part of this specification, and represent, in—

Figure 1, a view in side elevation of a sewing-machine containing my invention; Fig. 15 2, a front view of my improved feeding device; Fig. 3, a broken front view of the frame, showing the feed-plate bearing-surface and the feed-plate boss; Fig. 4, a detached view, in front elevation, of the feed-plate.

20 My invention relates to an improvement in feeding devices for sewing-machines, the object being to secure the widest range of adjustment in the length of the stitch by the simplest and most compact construction of 25 feeding device.

With these ends in view my invention consists in a feeding device having certain details of construction and combinations of parts, as will be hereinafter described, and 30 pointed out in the claim.

In carrying out my invention I employ a vertically-arranged feed-plate A, provided at its upper end with an integrally-formed arm B, constituting the cloth-feed and toothed or 35 roughened to adapt it to engage with the cloth. Toward its upper end the plate A is formed with a cam-opening C, the rear portion of which is shaped to form a cam-surface C' to coact with the operating-cam D, which is 40 mounted upon the projecting forward end of the driving-shaft F of the machine. A washer G, also applied to the projecting end of the said shaft, bears against the outer face of the feed-plate and holds the same against a raised 45 feed-plate bearing-surface H, formed upon the frame of the machine, as clearly shown in Fig. 3. The extreme forward end of the shaft is provided with a hook or looper I of any approved construction. The lower end 50 of the feed-plate is formed with a vertically-arranged open notch J, receiving a screw K, entering a boss L, formed upon the frame of

the machine and constituting a bearing for the lower end of the plate which is held against the boss by the head of the screw on which 55 the plate has a compound oscillatory and vertical movement. For the purpose of holding the cam-surface C' of the cam-opening C of the plate against the cam D or in position to be acted upon by the cam I employ a spring 60 H', hooked at one end through an opening a in the plate and hooked at its other end around a pin a' in the frame of the machine, the central portion of the spring being wound to form one or more coils which encircle the 65 boss L, before mentioned. As thus arranged the spring exerts a constant effort to swing the plate forward toward the front of the machine. For the purpose of adjusting the plate I employ an adjusting-lever N, having a cam-surface N', hung eccentrically upon a clamping-screw O, having a knurled head O', located in a lug H², forming an extension of the raised bearing-surface H, before mentioned. The cam-surface N' of the said lever is thus 70 brought into position to coact with the front edge of the upper end of the feed-plate, the forward movement of which under the action of the spring H' it limits. If the said adjusting-lever is turned down into the position in 75 which it is shown in Fig. 2 of the drawings, which it is shown in Fig. 2 of the drawings, it will clear the feed-plate altogether and allow the spring H' to act upon the plate and maintain the entire cam-surface C' thereof in engagement with the cam D, whereby the full 80 action of the cam D upon the plate will be obtained and the longest stitch within the capacity of the device secured; but if the cam-surface C' of the lever C is brought into engagement with the feed-plate by raising the 85 lever so as to push the plate rearwardly and prevent it from receiving the entire thrust of the operating-cam D then the stitch will be shortened. The extent to which the stitch will be shortened will of course depend upon 90 the extent to which the lever is raised and the plate is pushed inward.

It will thus be seen that by an extremely simple and compact device I am enabled to accurately adjust the machine for varying the 100 length of the stitch within a range wide enough to satisfy all of the ordinary requirements of sewing-machines.

I would have it understood that I do not

limit myself to the exact construction herein shown and described, but hold myself at liberty to make such changes and alterations as fairly fall within the spirit and scope of my 5 invention.

Having fully described my invention, what I claim as new, and desire to secure by Letters Patent, is—

In a feeding device for sewing-machines,
10 the combination with a frame formed with a raised, feed-plate bearing-surface, extended at its forward end to form a projecting lug, and also formed with a boss located directly below the said surface, of a vertically-arranged
15 oscillatory and vertically-movable feed-plate riding upon the said bearing-surface and upon the said boss, and at its upper end with a cam-opening containing a cam-surface, and formed at its lower end with a slot receiving a screw-
20 stud which holds the lower end of the plate against the said boss, an operating-cam con-

nected with the driving-shaft of the machine and located within the said cam-opening of the feed-plate, a spring connected with the said feed-plate, encircling the said boss, tending to move the cam-surface of the cam-opening of the plate toward the said operating-cam, and held upon the said boss by the slotted lower end of the feed-plate and the said screw, and an adjusting-lever pivoted to the 25 said projecting lug of the feed-plate bearing-surface in position to engage with the feed-plate to limit its movement under the action of the said spring.

In testimony whereof I have signed this 30 specification in the presence of two subscribing witnesses.

ROBERT PIERPONT.
